J. T. HANTON

TWISTER RING

Filed Sept. 5, 1922

Inventor:
John T. Hanton
by Chas. F. Randall
Atty.

UNITED STATES PATENT OFFICE.

JOHN T. HANTON, OF PUTNAM, CONNECTICUT.

TWISTER RING.

Application filed September 5, 1922. Serial No. 586,106.

To all whom it may concern:

Be it known that I, JOHN T. HANTON, a citizen of the United States, residing at Putnam, in the county of Windham, State of Connecticut, have invented a certain new and useful Improvement in Twister Rings, of which the following is a specification, reference being had therein to the accompanying drawings.

10 The invention is more particularly an improvement in connection with provisions for effecting lubrication of a ring and the traveler working thereon.

15 Special objects of the invention are to produce a ring of a construction not only providing for convenient application of lubricant, for retention thereof, for economy in the use of the lubricant, and for avoiding the production of yarn stained by the lubricant, but providing also for convenient and complete removal of grease, lint, etc., when it is undertaken to clean the ring.

20 The invention consists, essentially, in a twister ring or the like formed with an interior annular lubricant-containing recess tapering vertically toward one edge of the ring, preferably upward toward the top edge thereof, the said recess having a smooth, continuous wall, merging without break or shoulder with a smooth adjoining surface next toward such edge.

25 An illustrative embodiment of the invention is represented in the drawing, which shows in vertical diametrical section a twister ring embodying the invention, with a traveler thereon.

30 The ring 1 is flangeless interiorly, the upper and lower portions 11 and 12 of its inner surface adjacent the top and bottom edges 111 and 121 being smooth, plain and cylindrical. Intermediate said upper and lower cylindrical portions 11 and 12 is formed the annular recess 13. The latter, as aforesaid, tapers vertically, in this instance upwardly.

40 The wall of said recess from the lower portion of the recess upward is smooth and unbroken, and blends without shoulder or perceptible joint with the upper cylindrical portion 11. The traveler 2 is of a well-known form, and is applied to the ring in usual manner, namely, with its hooked upper and lower end-portions embracing the upper and lower edges of the ring, and with its body portion at the interior of the ring. A short

length of yarn *y* is shown in engagement 35 with the traveler.

In practice, preferably, hard grease is employed as a lubricant. This is applied within the recess, as for instance by means of one's finger or other suitable wiper, being 40 wiped into the recess so as substantially to fill the latter, and the excess being wiped away, so as to leave the upper and lower cylindrical portions of the interior surface of the ring, above and below the tapered recess, clean and free from anything more than a trace of the lubricant. As the ring heats up in operation under the friction of the traveler whirling around upon the same, the grease will soften sufficiently to allow 45 minute quantities thereof to creep upward and downward over the surfaces with which the traveler contacts in making its circuit. The recess will contain enough lubricant to answer for continuance of the twisting operation for a considerable number of hours 50 without replenishment or replacement.

When it is required to clear old grease, and the accumulated lint and other dirt, from the interior of the ring, they may be 55 readily wiped from the depths of the recess over the inclined surface of the wall of the latter and the cylindrical surface into which the inclined surface merges, and the said recess and said surfaces may be rendered 60 perfectly clean. There are no shoulders or the like behind or under which grease or dirt may lodge to interfere with this upward wiping and to create difficulty in effecting the clean removal of the old grease, etc. 65

The annular recess holds grease sufficient 70 to keep the ring properly lubricated throughout a large number of doffings. In practice, with a ring having a recess proportioned as in the drawing, I have found that 75 one application of grease to the ring answers throughout ten or twelve doffings. In the case of twister rings minus a recess, it is customary to apply grease to the rings after 80 every doffing, by wiping the grease by means 85 of one's finger upon the interior of the rings. This entails considerable waste of grease 90 and consumption of a very much greater quantity thereof for a given number of doffings than is necessary when rings are recessed. One reason therefor is that usually 95 more grease is applied than is needed. In addition, as soon as a frame is started up, 100

the greater part of the applied grease is scraped from the rings by the travelers, most of the grease thus removed finding its way to the floor. A considerable quantity thereof is caught by the yarns in process of being twisted together, with the result that stained yarn is produced. Making the rings with recesses to hold lubricant obviates loss by waste, obviates the production of stained 10 yard, and reduces very materially the number of times the rings require to be supplied with grease.

What is claimed as the invention is,—

1. A twister ring or the like formed with 15 an interior annular lubricant-containing recess, tapering vertically toward one edge of the ring, the said recess having a smooth,

continuous wall merging without break or shoulder with a smooth adjoining surface next toward such edge.

2. A twister ring or the like formed with an interior annular lubricant-containing recess, tapering vertically toward the upper edge of the ring, the said recess having a smooth, continuous wall merging without 25 break or shoulder with a smooth adjoining surface next toward the said edge.

In testimony whereof I affix my signature in presence of two witnesses.

JOHN T. HANTON.

Witnesses:
